UNITED STATES PATENT OFFICE.

ALLEN LOOMIS, OF ELKHART, INDIANA.

OCTAVE-KEY MECHANISM FOR MUSICAL INSTRUMENTS.

Application filed January 21, 1927. Serial No. 162,430.

This invention relates to musical instruments of the wood wind type and to the octave keys of such instruments. More particularly it is concerned with mechanisms of the type disclosed in my prior Letters Patent of the United States No. 1,585,295, dated May 18, 1926, and especially to the adaptation of such a mechanism to instruments having body tubes which are substantially 10 or nearly straight as to the parts where the octave holes are located.

The illustration of the invention herein given is one designed for straight soprano saxophones, but in principle, and in more or less nearly complete detail also, is applicable to other instruments of the wood wind type which have octave holes, wherefore such illustration is not to be construed as a limitation of the protection which I claim. 20 Such protection extends to all equivalent forms of the mechanism herein described, and the combination of such mechanism, or its equivalents, with all instruments of the wood wind type to which it may be usefully applied. The term "wood wind type" as here used, means musical instruments having the distinguishing characteristic of a body tube containing a vibratable column of air and lateral holes adapted to be opened and 30 closed for determining the length of the vibrating air column, and hence the pitch of the emitted note, whether actually made of wood, or of metal or of other material.

The objects of the invention are the same in general as set forth in my said prior patent, and include further the object of applying these principles in a compact and simple form, with a minimum of parts, to musical instruments having a substantially straight 40 body tube.

In the accompanying drawings,—

Fig. 1 is a perspective view showing the upper part of a straight saxophone having an octave key mechanism embodying this 45 invention applied thereto;

Fig. 2 is a diagrammatic or development view showing the parts of the octave key mechanism all resolved into a single plane.

Like reference characters designate the 50 same parts in both figures.

The numeral 3 designates the body tube of a straight, or substantially straight, saxophone, and typifies other instruments of the wood wind type also. Only so much of 55 the instrument and of the key mechanisms

applied thereto as is necessary for illustration of this invention are shown in the present drawings. But it is to be understood that a reed or other suitable appliances for causing vibration of the air column in the 60 tube, and suitable keys for the tone holes, are, or may be, used with any instrument containing this invention.

The numerals 4 and 5 represent the stoppers or covers which cover the lower and 65 upper octave holes respectively.

The stopper 4 is connected to an arm 6 secured to a sleeve 7 having a rotative bearing on a rod 8, which rod is mounted in posts or pillars 9 and 10 secured to the body 70 tube and is substantially parallel to said tube. Other sleeves, some of which are shown in this drawing and others are omitted for the sake of clearness, strung on the rod 8 prevent the sleeve 7 from being shifted endwise. The rod 8 provides a fixed axis for the stopper 4 approximately or nearly in the plane of the rim of the octave hole under the stopper, and so enables the stopper to open and close without sliding or scuffing 80 across such rim.

Sleeves 11 and 12 are also mounted on the pivot rod 8 adjacent to the supporting posts respectively. Sleeve 11 carries an arm 13 overlying the stopper 4 and a second arm 14 located where it will be out of the way of other parts. Sleeve 12 carries arms 15 and 16, the latter of which is parallel to the arm 14 and is connected therewith rigidly by a bridge rod 17. Arm 15 carries a stopper 90 or cover 18 for one of the tone holes of the instrument, and to this cover is secured a finger key 19. The arms 15 and 13 project to different sides of the pivot rod and approach different sides of the body tube, 95 clearing such tube by distances enough to permit limited angular movement. A spring 20 is mounted in the post or pillar 10 and bears on a hook 21 affixed to sleeve 12, normally depressing arm 13 against the cover 4 and raising the cover or stopper 18 and its attached finger key 19.

In this specification the term "raised", or terms of similar import, when applied to designate the movement of, or pressure applied to or by, a key or stopper, or parts associated therewith, signifies movement or pressure away from the body, whatever the direction of such movement or pressure may be with respect to the horizontal, and the 110

term "depressed", or terms of equivalent import, used in the same connection, means movement or pressure toward the body.

The stopper 5 for the upper octave hole 5 is carried by an arm 22 secured to a sleeve 23, which is mounted rotatively on a pivot or bearing pin held at its ends in posts or pillars 24 and 25 projecting from the instrument body. A second arm 26 is secured 10 to the sleeve 23, projecting therefrom in approximately the same direction as the arm 22, and carrying an abutment stud or finger 26^a. A spring 27 is mounted in the post 25 and bears on a hook 28 which projects 15 from the sleeve 23, said spring thereby applying force tending to close the stopper 5.

Connection is made between the two octave hole stoppers through a floating lever 29 mounted on a carrier consisting of two arms 20 31 and 32 and a sleeve 33 to which said arms are secured in parallel. Said sleeve is mounted to turn about a pivot rod 34 held in posts or pillars 35 and 36 projecting from the instrument body. The arms 31 and 32 25 carry, and are connected by, a pivot pin 37, on which the floating lever 29 and a hub or sleeve 38, secured thereto and fitting between the arms, have their bearing.

One arm of the floating lever 29 is connected to the arm 6 of the lower octave hole stopper by a pin 39 projecting from the arm 6 and pivotally supporting a slide block or cross head which occupies in a sliding manner a notch or slot or guideway in the 30 adjacent arm of the floating lever. The opposite arm 29^a of the floating lever extends under the abutment projection 26^a and is adapted to press against said abutment, and is to be pressed upon thereby under the influence of spring 27. A finger key 41 is secured to the sleeve 33 of the floating lever carrier and is adapted to be depressed by the performer's thumb. A spring 43 is mounted in the pillar 35 and is engaged with 40 a hook 42 on sleeve 33, tending to raise key 41 and depress the pivot pin 37. The keys 19 and 41 are typical in a broad way of any digit operated keys which may be applied to this or any equivalent mechanism to move 45 the parts at the will of the performer.

It will be noted that the pivot axes of both octave hole stoppers, the floating lever, and the floating lever carrier, are all substantially parallel to the body tube and to 50 each other; that both arms of the floating lever are in the same plane, or substantially so, which plane is transverse to their axis and to the body.

The tendency of the springs 20, 27 and 43 55 is to close both octave hole stoppers, all cooperating to this end. No spring is applied directly to the lower octave stopper arm 6, but this arm is freely rotatable about its pivot rod and is moved only as it is acted 60 on by the springs above named and the parts

affected thereby. It is normally held in closed position by the spring 20 acting through the presser arm 13. Spring 27 causes the arm 26 to press against the floating lever arm 29^a and to press the latter toward the instrument body, against which it bears, except when moved away therefrom by superior force. Its point of bearing is preferably protected by a cork or equivalent buffer 44. The spring 43 of the floating lever carrier exerts downward pressure on the floating lever pivot and thereby, in connection with the reaction of the floating lever arm 29^a on the instrument body, normally exerts a firm downward pressure on the arm 6, closing the octave hole even when the pressure of arm 13 is removed by depression of key 19.

Depression of key 19 alone raises the arm 13 and removes the pressure of spring 20 from the lower octave key, but without opening this hole. Depression of key 41 when the key 19 is also depressed has the effect of opening the lower octave hole by raising the main part of the floating lever and swinging it at the same time about the abutment finger 26^a as a fulcrum. But if key 41 alone is depressed, the floating lever is turned about the pin 39 as a fulcrum while its own pivot is raised, whereby its arm 29^a 95 raises the arms 26 and 22 and opens the upper octave hole. This last effect occurs because the spring 20 is made sufficiently stiff to exert greater resistance than is exerted by the spring 27 to the forces acting 100 upon and through the floating lever when the key 41 is depressed.

It follows from the actions just described that the upper octave hole is properly opened for playing notes in the middle and upper 105 registers of the instrument by the performer depressing the key 41 alone, and that where a transition from one register to another requires the conditions of the octave holes to be reversed, such reversal is automatically effected by the performer pressing upon or releasing the tone key 19 while continuing to press on the key 41. But both octave holes may remain closed for playing all notes in the lower register, provided 110 the performer does not then press upon the key 41.

What I claim and desire to secure by Letters Patent is:

1. In a musical instrument of the wood 120 wind type having two octave holes, stoppers for said holes pivotally supported from the instrument body, a floating lever carrier also pivotally supported from said body, a floating lever pivotally supported by said carrier, 125 an arm carrying one of said stoppers, another arm in rigid connection with the first named arm and projecting in the same direction as the latter from its pivot, engaged with one arm of said floating lever, and a 130

pivotal connection between the other arm of said floating lever and the other octave hole stopper.

2. In a musical instrument of the wood wind type having two octave holes, stoppers for said holes pivoted on fixed axes substantially parallel to the body of the instrument, an arm carrying one of said stoppers, a second arm rigidly connected with the first named arm and extending in the same direction as said stopper from its axis, a floating lever carrier supported on a substantial parallel axis, and a floating lever pivotally mounted on said carrier at one side of the last named axis and on an axis approximately parallel thereto, said floating lever having arms extending to different sides of its axis and engaged respectively with the before named second arm and with the other octave hole stopper.

3. A musical instrument of the wood wind type having a substantially straight body and two octave holes, a stopper pivotally supported for closing and opening one of said holes, a floating lever having one arm coupled to said stopper and having a second arm arranged to bear on the instrument body, a carrier pivotally supported from the instrument body and to which the floating lever is pivoted, a second octave hole stopper mounted to turn about an axis substantially parallel to the instrument body, an arm longitudinally separated from the last named stopper to turn about the same axis and rigidly connected therewith, said arm being arranged to engage the second floating lever arm and in approximately the same plane therewith, and a spring mounted to apply force to said connected octave hole stopper and arm urging the stopper toward its hole and the arm toward the floating lever.

4. In a musical instrument of the wood wind type, a substantially straight body tube, a longitudinally extending pivot supported from said tube, an upper octave hole stopper, an arm carrying said stopper rotatably mounted

on said pivot, a second arm rigidly connected to said stopper mounted rotatably on the same pivot and extending therefrom in the same direction as the stopper carrying arm, a floating lever carrier pivotally supported from the body tube, a floating lever pivotally mounted on said carrier at one side of the axis thereof having one arm extending between the body tube and abutting portion of the second named arm, a second octave hole stopper, and flexible coupling means between the last named stopper and a second arm of the floating lever.

5. A musical instrument of the wood wind type having a substantially straight body and octave holes spaced apart longitudinally, stoppers for said octave holes, arms carrying the respective stoppers, both mounted to turn about axes substantially parallel with the instrument body, a floating lever having two arms in approximately the same plane transverse to the body tube, one of which arms is articulated to the arm of the lower octave hole stopper and the other lies adjacent to said body, a carrier for said floating lever pivotally supported from the body on an axis substantially parallel to the body, and to which the floating lever is pivotally connected on an axis likewise substantially parallel to the body, a spring acting on said carrier tending to depress the floating lever pivot, a spring acting on the upper octave hole stopper tending to depress said stopper, and an arm pivotally mounted on the same axis as the arm of the upper octave hole stopper and extending in the same direction as said stopper arm from said axis and in such rigid association with the stopper arm as to be depressed by the last named spring, said last named arm being arranged to bear on and depress the second named arm of the floating lever.

In testimony whereof I have affixed my signature.

ALLEN LOOMIS.
